(No Model.)

I. N. ELLIOTT & P. A. REID.
MECHANICAL MOVEMENT.

No. 379,775.

Patented Mar. 20, 1888.

UNITED STATES PATENT OFFICE.

ISAAC N. ELLIOTT AND PETTIS A. REID, OF RICHMOND, INDIANA.

MECHANICAL MOVEMENT.

SPECIFICATION forming part of Letters Patent No. 379,775, dated March 20, 1888.

Application filed August 30, 1886. Renewed December 22, 1887. Serial No. 258,681. (No model.)

To all whom it may concern:

Be it known that we, ISAAC N. ELLIOTT and PETTIS A. REID, of Richmond, in the county of Wayne and State of Indiana, have invented 5 a new and useful Improvement in Mechanical Movements, which improvement is fully set forth in the following specification and accompanying drawings, in which—

Figure 1 is a front view of our improved mechanical movement; Fig. 2, a side view of the same; Fig. 3, a perspective view; Fig. 4, a plan view through line X X of Fig. 1, and Fig. 5 a front view of a modification.

As is well known, the reel or take-up of a fabric or fence weaving machine is usually defective in its operation on account of the increased size of the fabric upon the reel just in proportion to the thickness of the fabric wound thereon, so that it is difficult to gage the speed 20 of the rotation of the reel, and thus accommodate it to the speed of the fabric as received from the machine.

Our device relates to an improvement in mechanical movements so disposed as to be 25 adapted for a take-up for reels or winders; and it consists of the combination, with a shaft which may be the carrying-shaft of a reel or winder, a ratchet-faced wheel, a disk at the side of the said wheel, a pawl-carrying arm 30 journaled on the said shaft, and a rod whereby said arm is connected with means for vibrating the same, of a screw-threaded shaft mounted within the said arm, a disk upon the said screw-threaded shaft, bearing upon the disk upon the shaft, and a block to which the actuating-rod 35 is connected, mounted upon the said arm and connected to engage with the said screw-threaded shaft. By this combination of devices, as the reel or winder increases in diameter, the screw-threaded shaft is rotated and the said block is moved outwardly from the shaft, thereby shifting outwardly the actuating-rod and proportionally decreasing the speed of the 40 rotation of the reel.

In the accompanying drawings, A represents 45 an ordinary frame, to which is journaled the horizontal shaft B, which may carry any suitable reel or winder. This shaft B is provided with a ratchet-faced wheel, C, provided at one 50 side with a series of graduated retaining-pawls, D, so disposed as to prevent back movement

of the ratchet-wheel C. Operating integrally therewith or attached at the side of the wheel C is a metal disk, E. Journaled at its inner end on the shaft B we provide a frame or arm, 55 F, composed of two parts, G and H. Within this frame F we provide a shaft, I, journaled therein, provided almost its entire length with a screw-thread, J. The end adjoining the shaft B we provide with a friction-wheel, K, secured 60 in position upon the said shaft by means of the set-screw L, so that the said friction-wheel K may be moved to or from the shaft B to adjust it inwardly or outwardly upon the face of the disk E.

Upon the frame F we provide a transverse piece or block, M, the ends of which have inturned lugs N, so disposed as to clasp the edges of the pieces H and G, which are thus designed to act as ways. Centrally this piece M 70 has a threaded opening, O, through which the threaded shaft I passes, so that in the rotation of this said shaft I the transverse piece M will be moved outwardly upon the arm F. Upon this arm F—say near the upper end and at 75 suitable distance therefrom along its length—are brackets R, having slots or ways Q, in which slots or ways is placed the series of pawl-bars P, so as to be movable up or down, the lower ends of the said pawl being so disposed as to 80 engage with the ratchet-face of the wheel C. To one end of this transverse piece M a connecting-rod, S, is attached, having a connection with the operating mechanism, by means of which power is transmitted to this device, 85 as shown, for example, in the patent to I. N. Elliott, No. 343,232, June 8, 1886.

A modification of the pawl P is shown in Fig. 5, wherein in lieu of the said bar P and pawls D we provide eccentric clutches T, so disposed 90 as to bind against the periphery of the disk E.

The operation of our device is as follows: The connecting-rod S, attached to the transverse piece M on the frame F, has a reciprocal motion. When it is moved toward the right, the 95 wheel C and the reel upon the shaft B are stationary, causing the friction-wheel K to rotate on disk F and turn the screw; but when the motion of the connecting-rod S is reversed the pawl P, engaging with the ratchet-face of the 100 wheel C, partially rotates the said wheel C, thus operating the shaft and reel, no rotation of the

shaft I being effected. At every movement of the connecting-rod S the take-up of the goods wound attached to the reel is effected, and in order that the speed of the reel may be decreased just in the proportion that the goods on the reel increase in size the rotary movement of the shaft I, occasioned as the arm F moves to the right, gradually moves the piece or block M, to which the connecting-rod S is attached, outwardly from the shaft B, and thus the speed of the reel is decreased.

The friction-wheel K, provided with set-screw L, is so disposed as to be adjustable radially against the face of the disk E, so that it may be placed in any desired position at any distance from the shaft B to correspond with the thickness of the fabrics to be wound upon the reel to correspond with the varying speed of the device.

20 The piece or block M may be put in motion for a new roll or bale by rotating reversely the ratchet-wheel C until the screw carries the bar or piece to the desired point. The reverse rotation of the ratchet-wheel C is made while the machine is at rest, and is done by any simple method the operator may choose.

Having described our invention, what we claim as new is—

1. In a mechanical movement, the combination of the main shaft B, an arm, F, journaled at its inner end on said main shaft and having

a block, M, attached thereto, and a threaded shaft, I, movable in brackets thereon, a friction ratchet-wheel, K, means whereby the said wheel is adjustably secured on said shaft, the wheel C, and the disk E, substantially as described.

2. The combination, with the shaft B, having thereon the ratchet-faced wheel C and the disk E, of the arm F, having attached thereto 40 the transverse piece M, the threaded shaft I, movable therein, the friction-wheel K on said shaft, and the pawl P, movable in brackets on said arm, substantially as described.

3. The combination of the ratchet-faced 45 wheel C, the disk E, attached to the side of said wheel, the shaft B, the pawls D, the arm F, journaled on the shaft B, the shaft I, journaled in said frame, the friction-wheel K, adjustable by a set-screw on the shaft I, with the 50 transverse piece M, and the connecting-rod S, and the pawl P, substantially as and for the purpose set forth.

In testimony that we claim the foregoing we have hereunto set our hands, this 25th day of 55 May, 1886, in the presence of witnesses.

ISAAC N. ELLIOTT.
PETTIS A. REID.
